UNITED STATES PATENT OFFICE.

BENJAMIN BROWNSTEIN, OF ELLWOOD CITY, PENNSYLVANIA.

PIPE-THREAD PROTECTOR.

Application filed June 8, 1926. Serial No. 114,460.

This invention relates to thread protectors for pipes, these protectors being used to prevent the threads of pipes from being damaged in handling or shipping.

One of the objects of the present invention is to provide a thread protector which is particularly adapted for small pipe and in which the protector is seamless, which will not be expensive as it may be made from thin material and which thus may be thrown away when the pipe is used and a further object is to provide a protector of this character which may be made in a punch press to eliminate the expensive operation of threading the different numbers and taper of threads for any given size.

Another object is to provide a construction of this character formed of relatively thin sheet metal cup-shaped in general form to extend over the end of the pipe and engage the threads thereof and so form the central portion of the protector as to provide for the engagement therewith of a wrench bar whereby the protector may be applied or removed.

My invention is illustrated in the accompanying drawings, wherein:—

Figure 1 is a top plan view of a thread protector constructed in accordance with my invention;

Fig. 2 is a vertical sectional view through a pipe with my thread protector applied thereto;

Fig. 3 is an elevation of the structure shown in Figure 2.

Referring to these drawings it will be seen that 10 designates a cup-shaped body of relatively thin metal so formed as to provide the inwardly turned portion 11 at its upper end and an outwardly bulged portion 12, this bulged portion being longitudinally slotted as at 13 whereby to receive a wrench bar or like implement shown in dotted lines in Figures 2 and 3 and designated 14 whereby the thread protector may be screwed onto or off from a pipe.

The body 10 inward of the flange 11 is formed with a U-shaped slot 15 and the tongue 16 defined by this slot is inwardly bent at a slight angle so as to engage the

threads of a pipe A. These lugs or tongues 16 are slightly resilient and when the protector is screwed upon the pipe these tongues prevent any detachment of the protector except by unscrewing the same. Any number 55 of thread engaging tongues may be used depending on the size of the pipe. I do not wish to be limited to the exact form of the embossed or protuberant portion 12 as this may have other shapes than that illustrated. 60

It will be seen that the flange 11 constitutes a stop to bear against the upper end of the pipe and this locks the pipe in the protector.

I claim:—

1. A pipe thread protector having a cup-shaped body of relatively thin metal adapted to be placed over and enclose the end of a pipe, the body being formed with inwardly extending tongues adapted to engage the 70 thread of the pipe, one end of said body having a marginal portion and a central portion extending outward beyond the plane of the marginal portion and this outwardly extended portion being diametrically slotted to 75 receive a wrench bar.

2. A pipe thread protector comprising a cup-shaped body of relatively thin metal and having inwardly extending thread engaging tongues formed in its side wall, one end of 80 the body being formed to provide an annular marginal portion adapted to engage the extremity of a pipe and constitute a stop, the material inward of said marginal portion being embossed and being transversely 85 slotted to provide means for the engagement of a wrench bar therewith.

3. A pipe thread protector having a cup-shaped body of thin metal adapted to be placed over and enclose the end of a pipe, the 90 body being formed with relatively short, yieldable, upwardly and inwardly extending members adapted to engage the threads of the pipe, one end of the body having a diametrically extending slot adapted to receive 95 a wrench bar.

In testimony whereof I hereunto affix my signature.

BENJAMIN BROWNSTEIN.
